A. E. Hart.

ATTORNEY.

UNITED STATES PATENT OFFICE.

PHILIP K. WILLIAMS, OF GLASTONBURY, CONNECTICUT, ASSIGNOR TO THE J. B. WILLIAMS COMPANY, OF GLASTONBURY, CONNECTICUT, A CORPORATION OF CONNECTICUT.

SOAP-HOLDER.

1,331,549.

Specification of Letters Patent. Patented Feb. 24, 1920.

Application filed March 20, 1919. Serial No. 283,753.

To all whom it may concern:

Be it known that I, PHILIP K. WILLIAMS, a citizen of the United States, and a resident of Glastonbury, county of Hartford, 5 and State of Connecticut, have invented certain new and useful Improvements in Soap-Holders, of which the following is a specification.

This invention relates, in general, to 10 holders for bars of soap and the like, such for instance as shaving sticks, and has as one of its objects to provide a holder which will permit of all the shaving stick being used up, thus entirely avoiding all waste, 15 and which may be readily and quickly re-filled with a new stick of soap after an old stick has been entirely utilized.

A further object of the invention is to 20 make certain improvements in the structure disclosed in the patent to F. Riensenberg, Patent No. 1,194,427, dated August 15, 1916, and which improvements will be more particularly pointed out in the following description of my invention.

25 The above and other objects of my invention are obtained in the structure described in the following detailed description, and illustrated in accompanying drawings, and wherein:—

30 Figure 1 is a longitudinal sectional view taken centrally through the holder, the soap medium being shown in elevation.

Fig. 2 is an elevational view with the 35 parts shown in separated position, a portion of the soap medium and the supporting member or base being in section for the purpose of clearness.

Referring in detail to the drawings, 10 designates a soap medium supporting member or base, having, in the present illustrative disclosure, at each end a plain, flat surface against which is fitted the plain, flat 40 end surfaces of the sticks of soap 11. Suitable means is interposed between the abutting flat surfaces of the soap and base so as to firmly unite the same, and this securing means indicated by the heavy black line 12 in Fig. 2, may be of any material which will readily wear away, such as paraffin. In 45 securing the sticks of soap or the like to the base, the paraffin is brought to a proper heat, the end surfaces of the base and stick dipped into the paraffin and then the parts are butted together under a slight pressure 50 until the paraffin hardens. This provides a

very strong attachment between the parts, amply sufficient to withstand ordinary use to which a soap medium of this sort is subjected. The base 10 is formed of some relatively cheap material which may be readily 60 and quickly fashioned into shape, preferably wood being used for this purpose, so that the cost of these bases is so extremely low as to be almost negligible and thus, after the soap stick, or sticks, attached to 65 the same have been used up, the old base may be discarded without entailing any appreciable waste and a new base substituted in its place.

The body portion of the holder is formed 70 of two parts so constructed as to detachably receive the base or block 10, and these parts are readily connected and disconnected when the holder is to be refilled. In the drawings I have shown the body portion 75 of the holder as comprising two rings, 13 and 14, and the construction is such that when these rings are secured together an internal groove 15 is provided which is adapted to receive a circumferential rib 16 80 on the base 10. It is of course evident that with slight changes, the positions of the groove and rib may be reversed. The rings 13 and 14 are adapted to be slipped over the free end of the sticks of soap and onto the 85 opposite ends of the block 10. The two parts of the body portion may be secured together in any suitable manner, but in the present instance I have shown the rings as having complementary screw threads 17. 90

The numerals 18 designate caps or covers which fit over the sticks of soap 11, and the open ends of these covers detachably receive the opposite ends of the body portion of the holder. For the purpose of illustration I 95 have shown the caps as having, adjacent to their open ends, internal threads which receive the external threads 19 on the rings 13 and 14. For the purpose of preventing the rings 13 and 14 from being unscrewed 100 from each other when the caps are unscrewed from the rings, the threads 17 run in one direction, right-handed, for instance, and the threads 19 run in the other direction, that is, left-handed.

105 It will be noted from the drawings that the length of the rings 13 and 14 is such that when they are secured about the base 10, the opposite ends of this base extend slightly beyond the ends of the rings and 110

the purpose of this arrangement is to permit the soap to be entirely worn away so that there is no wastage of the soap whatsoever.

When it is desired to apply soap to the face

- 5 by rubbing the same thereon, one of the caps 18 may be removed and the exposed soap medium applied, the other cap serving as a handle of substantial size, permitting the ready manipulation of the holder and at 10 the same time this latter cap protects that end of the shaving stick which is not in use from exposure and handling.

When the soap medium at one end of the base 10 has been entirely used up, that is

- 15 when the flat face of the base 10 has become exposed, the cap at the unused end of the stick may be removed and the cap covering the used end of the stick employed as a handle. When both the soap sticks 20 have been completely used up, the two parts 13 and 14 of the body portion of the holder may be readily detached from each other and the spent base 10 removed, and a new 25 stick substituted in its place. The substitution of a new stick is quickly and readily accomplished and the bases are of extremely simple construction, are formed of some cheap material which is easily fashioned into shape, are devoid of screw threads 30 and the like requiring expensive operations, and do not require great care in their manufacture, so that the cost of the bases is hardly appreciable and therefore they may be discarded without constituting waste.

- 35 In accordance with the provisions of the patent statutes, I have described the principle of operation of my invention, together with the apparatus which I now consider to represent the best embodiment thereof; but 40 I desire to have it understood that the apparatus shown is only illustrative, and that the invention can be carried out by other means.

What I claim is:—

- 45 1. A soap holder comprising a base to which a soap medium is secured, a body portion adapted to be detachably secured to said base and composed of two parts detachably connected together, and a cap inclosing the soap medium and detachably engaging said body portion.

- 50 2. A soap holder comprising a base to which a soap medium is secured, a body portion comprising two parts, interlocking means on the base and body portion, means for detachably securing together the two parts of the body portion, a cap inclosing the soap medium, and means for detachably securing the cap to the body portion.

- 55 60 3. A soap holder comprising a cylindrical base having a face against which the end surface of a soap medium abuts, securing means interposed between said abutting surfaces, a body portion detachably receiving said base with the face of the base extend-

ing beyond the body portion, and a cap inclosing the soap medium and detachably engaging said body portion.

4. A soap holder comprising a base having a circumferential rib and a face against which a soap medium abuts, securing means interposed between said abutting faces, a body portion composed of two members encircling the base and locking said rib therebetween, said body portion terminating short of said face of the base, means for detachably securing the two members of the body portion in position, and a cap inclosing the soap medium and detachably connected to said body portion.

5. A soap holder comprising a base to the opposite ends of which a soap medium is secured, a two-part holding ring, the parts of which are detachably secured together about said base, and a cap for each of said soap mediums and engageable with opposite ends of said ring.

6. A soap holder comprising a base to the opposite ends of which a soap medium is secured, a body portion comprising two rings, interlocking means on said base and body portion, means for detachably securing said rings together about said base, a cap inclosing the soap medium at each end of said base, and means on each ring for receiving the open ends of said caps.

7. A soap holder comprising a base having a face at each end and against each of which faces the end surface of a soap medium abuts, securing means interposed between said abutting surfaces, a two-part ring encircling and holding said base with the ends of said base extending beyond said ring, means for detachably securing the parts of said ring together, and a cap for inclosing each of said soap mediums and receiving opposite ends of said ring.

8. A soap holder comprising a base having a face against which the end surface of a soap medium abuts, securing means interposed between said abutting faces, a body portion detachably receiving said base, and a cap inclosing the soap medium and detachably engaging said body portion.

9. A soap holder comprising a base, means for securing a soap medium thereto, a body portion adapted to be detachably secured to said base and composed of a plurality of parts detachably connected together, and a cap inclosing the soap medium and detachably engaging said body portion.

10. A soap holder comprising a base, means for securing a soap medium to each end of said base, a multi-part holding ring, the parts of which are detachably secured to said base, and a cap for each of said soap mediums and engageable with the opposite ends of said ring.
